UNITED STATES PATENT OFFICE.

HARMON E. GROOMS, OF COLUMBUS, GEORGIA.

DESIGN FOR A TIRE-TREAD.

55,378.

Specification for Design.

Patented June 1, 1920.

Application filed March 15, 1919. Serial No. 282,989. Term of patent 14 years.

To all whom it may concern:

Be it known that I, HARMON E. GROOMS, a citizen of the United States, residing at Columbus, in the county of Muscogee and State of Georgia, have invented a new, original, and ornamental Design for a Tire-Tread, of which the following is a specification, reference being had to the accompanying drawing, forming part thereof.

The figure is a perspective view of a portion of a tire tread showing my new design.

I claim:—

The ornamental design for a tire tread, as shown.

HARMON E. GROOMS.
